EXTENSION TABLE TOP EQUALIZER

Frederick B. Walter, Wabash, Ind., assignor to
 B. Walter & Company, Inc., Wabash, Ind., a
 corporation of Indiana

Application August 26, 1933, Serial No. 686,909

5 Claims. (Cl. 45—115)

The object of my invention is to produce an inexpensive but efficient equalizer mechanism for connecting two sliding table top sections in such manner that sliding force applied to either of 5 said top sections will be automatically transmitted to the other section to produce proper co-ordinated movement thereof whereby the adjacent edges of said top sections may be contacted at the middle of the supporting frame or 10 against the opposite edges of an interposed extension leaf.

The accompanying drawing, which is a plan with portions of the sliding tops broken away, 15 illustrates my invention.

15 In the drawing 10, 10 indicate the side rails and 11, 11 the end rails of the usual leg-supported frame. Extending between the side rails, intermediate the end rails are stretcher bars 12, 12 to which, and adjacent end rails 11, are secured 20 the stationary slide bars 13, 13 with which vertically interlock slide bars 14 are secured to the under faces of the sliding tops 15.

Extending between the stretcher bars 12, to 25 one side of the medial length of the table, is a horizontal stretcher bar 16 to the inner vertical edge of which may be secured the supporting brackets of a folding leaf 17.

Secured to the upper face of the stretcher bar 16 is a metal base strip 18 to the opposite ends 30 of which are pivoted levers 19 and 20. Pivotally connected to the outer end of each of levers 19 and 20 is a link 21 to the outer end of each of which is pivotally connected a plate 22 provided with appropriate perforations 23 at its ends to 35 receive fastening screws passing upwardly into the adjacent sliding top section 15.

Pivotally connected at 19' and 20', respectively, to the levers 19 and 20 is a link 25 which 40 is preferably, though not necessarily, provided with a longitudinally extending slot 26 into which is projected a pin 27 carried by strip 18, the slot being so proportioned that pin 27 will engage one end thereof so as to limit the outwardly sliding movement of the table top sections, the inward movement of said sections 45 being, of course, limited by contact at their adjacent inner edges.

As shown in the drawing the parts are so proportioned that the total travel of the two sliding top sections will be equal when the adjacent inner edges of the sliding top sections are separated by an amount equal to the width of the extension leaf 17.

I claim as my invention:

55 1. In a sliding-top table, the combination with

the leg-supported frame and two top sections 60 slidably mounted thereon, of two levers pivotally anchored on the main frame beneath the top sections with their fulcrums spaced lengthwise of the line of slide of the sliding top sections, a link 65 pivotally associated with each lever and the adjacent top section, and a connecting link extending between and connecting said levers in such manner as to compel opposite movement of the link ends of said levers, and inter-engag- 65 able elements, one carried by the leg-supported frame and the other by said connecting link to limit outward movement of said levers.

2. In a sliding-top table, the combination with 70 the leg-supported frame and two top sections slidably mounted thereon, of two levers pivotally anchored on the main frame beneath the top sections with their fulcrums spaced lengthwise of the line of slide of the sliding top section, a link 75 pivotally associated with each lever and the adjacent top section, and a connecting link extending between and connecting said levers in such manner as to compel opposite movement of the link ends of said levers.

3. An equalizer for sliding table tops comprising 80 a base bar, two levers pivotally anchored at the opposite ends of said base bar, a connector link pivotally connected at its ends to said levers in such manner as to compel opposite movement thereof, and two links each pivotally connected 85 to the outer end of one of said levers and provided at its outer end with means by which it may be attached to a sliding section of a table top, and inter-engaging means carried respectively by the base bar and connector link for 90 limiting movement of the connector link relative to the base bar in one direction.

4. An equalizer for sliding table tops comprising 95 a base bar, two levers pivotally anchored at the opposite ends of said base bar, a connector link pivotally connected at its ends to said levers in such manner as to compel opposite movement thereof, and two links each pivotally connected to the outer end of one of said levers and provided at its outer end with means by which it 100 may be attached to a sliding section of a table top.

5. An equalizer for sliding table tops comprising 105 a base bar, two levers pivotally anchored at the opposite ends of said base bar and each provided at its outer end with means for engagement with a sliding table top section, and a connector link pivotally connected at its ends to said levers in such manner as to compel opposite movement thereof.

FREDERICK B. WALTER. 110
